RELAY

Walter Brandt, Vienna, Austria, assignor to
 Western Electric Company, Incorporated, New
 York, N. Y., a corporation of New York

Application January 7, 1937, Serial No. 119,428
 In Austria March 23, 1936

8 Claims. (Cl. 200—104)

This invention relates to relays and more particularly to relays which are responsive either to direct current energization or to energization by alternating currents of one or more predetermined frequencies.

In telephone systems in which certain lines serve two or more substations it is necessary to provide facilities for selecting any one of the substations after the common line has been seized. For this purpose the relay in accordance with this invention, several modifications of which have been disclosed, is provided with a set of contact springs which is operated in the usual manner by the attraction of the relay armature in response to the energization of its winding by direct current and with one or more additional sets of springs which are so tuned as to be operated when the relay winding is energized by alternating currents of one or more predetermined frequencies. It is to be understood, however, that the relay of this invention is equally applicable to systems other than party line telephone systems.

For a clearer understanding of the invention reference may be had to the following detailed description taken in connection with the accompanying drawing of which:

Fig. 1 shows one embodiment of the invention;

Fig. 2 shows a second embodiment of the invention;

Fig. 3 is a side elevation of a further embodiment of the invention; and

Fig. 4 is an end elevation of the relay structure disclosed in Fig. 3.

Referring now to Fig. 1, the relay disclosed therein comprises a heel-piece 1, a core 2 secured thereto by the screw 3, an energizing winding 4 on the core 2, an armature 5 pivoted on the forward end of the heel-piece 1 and cooperating with the pole-face of the forward end of the core 2 and a spring pile-up 6 insulatedly supported on the heel-piece 1. The movable springs of the pile-up 6 are operable into engagement with the stationary springs of the pile-up by the operating studs 7 and 8 through the movement of the rear end of the armature 5 when the armature is attracted toward the core 2 by the energization of the winding 4. In addition, a pair of tuned resonant springs 9 and 10 is provided, spring 9 being secured to a stationary support 11 and spring 10 being insulatedly secured to the armature 5. The springs 9 and 10 are so tuned as to become closed in response to a definite frequency. If desired, a second pair of similar springs tuned to be responsive to a different frequency.

frequency may be similarly mounted with respect to the armature 5. A spring member 12 is also provided attached at one end to the heel-piece 1 by screws 13 and with its free end overlying the pole-face of the end of core 2. Instead of the spring member 12 an elastic bumper of felt, rubber or other similar material may be used.

If now direct current is applied to the winding 4, the armature 5 is attracted toward the core into engagement with the spring 12 and the contact springs of the spring pile-up 6 are operated in the usual manner. If now alternating current of a predetermined frequency is applied to the winding 4 the armature vibrates in response thereto due to its engagement with the spring member 12, thereby causing the spring 10 to vibrate with such amplitude as to engage with the fixed spring 9.

The relay shown in Fig. 2 is similarly provided with a heel-piece 21, core 22 secured thereto by the screw 23, winding 24, armature 25 and spring pile-up 26, but the tuned resonant spring 30 and fixed spring 29 are mounted to be operated not by the vibration of the armature 25, but by a separate armature. To accomplish this the fixed spring 29 is insulatedly mounted on a bracket 31 secured to the relay structure by the screw 23. The spring 30 is secured to the heel-piece 21 by screw 32 and a small armature 33 is attached by a screw 34 to the spring 30 and cooperates with an opening 35 in the heel-piece.

When direct current is applied to the winding 24, the armature 25 is attracted toward the core 22 thereby operating the springs of the pile-up 26. If now alternating current of a predetermined frequency is applied to the winding 24 the small armature 33 is vibrated within the opening 35 in the heel-piece transmitting its vibrations to the spring 30 which will thereupon engage with the fixed spring 29.

In Figs. 3 and 4 a relay of the flat type is disclosed which functions in the same general manner as the relay disclosed in Fig. 1. This relay comprises a heel-piece 41, a core 42 secured thereto by the screw 43, an energizing winding 44 on the core 42, an armature 45 pivoted by a knife edge on the forward end of the heel-piece 41 and a spring pile-up 46 operable by the operating stud 47 carried by the armature. The forward end of the armature 45 cooperates with the pole piece 48 secured to the forward end of the core 42 and is provided with two ears 49 and 50 between which a steel wire or ribbon 51 is stretched. To afford clearance for the free vibration of the wire 51, the pole piece 48 is provided

with a laterally extending groove 52 as most clearly shown in Fig. 3. With the armature 45 in its normal or unattracted position the mid-point of the wire 51 rests upon the end of adjusting screw 53 which is threaded through the pole piece 48.

In addition to the spring pile-up 46 a pair of resonant springs 54 and 55 is provided, the spring 54 being insulatedly attached to the free end of armature 45 and spring 55 being insulatedly attached near the rear end of the heel-piece 41.

When direct current is applied to the winding 44, the armature is attracted against the tension of the wire 51 toward the pole-piece 48 operating the springs of the spring pile-up 46. If now alternating current of a predetermined frequency is applied to the winding 44, because of the elastic support of the free end of the armature by the wire 51 engaging with the end of the screw 53, the armature will vibrate in response to the alternating current transmitting its vibrations to the spring 54 which will then engage with spring 55.

What is claimed is:

- 25 1. A relay having a winding and an armature, contact springs operable by said armature in response to the excitation of said winding by direct current, and a set of resonant springs operable into engagement in response to the excitation of said winding by alternating current of a definite frequency but inoperable in response to the excitation of said winding by direct current.
- 30 2. A relay having a winding and an armature, contact springs operable by said armature in response to the excitation of said winding by direct current, a resonant spring mounted on said armature, a fixed spring associated therewith, and spring means associated with said armature for causing said armature to vibrate to cause the engagement between said resonant spring and said fixed spring in response to the excitation of said winding by alternating current of a definite frequency, said resonant and fixed springs being unengageable in response to the excitation of said winding by direct current.
- 35 3. A relay having a winding, a pole piece and an armature, contact springs operable by said armature in response to the excitation of said winding by direct current, a resonant spring mounted on said armature, a fixed spring associated therewith, and a spring member interposed between the pole piece and said armature for causing said armature to vibrate to control the engagement between said resonant spring and said fixed spring in response to the excitation of said winding by alternating current of a definite frequency, said resonant and fixed springs being unengageable in response to the excitation of said winding by direct current.
- 40 4. A relay having a winding, a core and an armature, contact springs operable by said armature in response to the excitation of said winding by direct current, a resonant spring mounted on said heel-piece, a fixed spring associated therewith, and means for causing the engagement of said resonant and fixed springs in response to the excitation of said winding by alternating current of a definite frequency, said means comprising an auxiliary armature secured to said resonant spring and cooperating with said heel-piece, said resonant and fixed springs being unengageable in response to the excitation of said winding by direct current.

5 mounted on said armature, a fixed spring associated therewith, and an elastic member interposed between the end of said core and said armature with which said armature engages upon its attraction for causing said armature to vibrate to control the engagement between said resonant spring and said fixed spring in response to the excitation of said winding by alternating current of a definite frequency, said resonant and fixed springs being unengageable in response to the excitation of said winding by direct current.

10 5. A relay having a winding, a pole piece and an armature, contact springs operable by said armature in response to the excitation of said winding by direct current, a resonant spring mounted on said armature, a fixed spring associated therewith, and means interposed between said armature and said pole piece for causing said armature to vibrate to control the engagement between said resonant spring and said fixed spring in response to the excitation of said winding by alternating current of a definite frequency, said means comprising a spring member carried by said armature and an adjustable stop in engagement therewith, said resonant and fixed springs being unengageable in response to the excitation of said winding by direct current.

15 6. A relay having a winding and an armature, a resonant spring mounted on said armature, a fixed spring associated therewith, and means for causing said armature to vibrate to control the engagement of said springs in response to the excitation of said winding by alternating current of a definite frequency, said means comprising an elastic member carried by said armature and an adjustable stop in engagement therewith.

20 7. A relay having a winding, an armature and a pole piece, a resonant spring mounted on said armature, a fixed spring associated therewith, and means for causing said armature to vibrate to control the engagement of said springs in response to the excitation of said winding by alternating current of a definite frequency, said means comprising a wire stretched between two supports carried by the free end of said armature, and an adjustable stop mounted in said pole piece and in engagement with the mid-point of said wire.

25 8. A relay having a winding, a heel-piece, a core and an armature, contact springs operable by said armature in response to the excitation of said winding by direct current, a resonant spring mounted on said heel-piece, a fixed spring associated therewith, and means for causing the engagement of said resonant and fixed springs in response to the excitation of said winding by alternating current of a definite frequency, said means comprising an auxiliary armature secured to said resonant spring and cooperating with said heel-piece, said resonant and fixed springs being unengageable in response to the excitation of said winding by direct current.

30 WALTER BRANDT.
